Primary Examiner — T Chase Nelson*Assistant Examiner* — Kelly L Gross(74) *Attorney, Agent, or Firm* — Eversheds Sutherland (US) LLP(57) **CLAIM**

The ornamental design for a handle for medical instruments, as shown and described.

DESCRIPTION

FIG. 1 is a perspective view of a handle for medical instruments showing our new design;
 FIG. 2 is a front view thereof;
 FIG. 3 is a rear view thereof;
 FIG. 4 is a left side view thereof;
 FIG. 5 is a right view thereof;
 FIG. 6 is a top view thereof; and,
 FIG. 7 is a bottom view thereof.
